CLAIM

The ornamental design for a structural building panel, as shown and described.

DESCRIPTION

Cross-Reference To Related Applications: U.S. patent application Ser. Nos. 29/651,180; 29/505,814

FIG. 1 is a perspective view showing my new design for a structural building panel from the front, top, and right side; FIG. 2 is a perspective view showing the design from the front, top and left side;

FIG. 3 is a perspective view showing the design from the rear, top and left side;

FIG. 4 is another perspective view of the design showing the design from the top, rear and left side;

FIG. 5 is a perspective view showing the design from the bottom, rear and left side;

FIG. 6 is a front elevational view thereof;

FIG. 7 is a rear elevational view thereof;

FIG. 8 is a right-side elevational view thereof;

FIG. 9 is a left-side elevational view thereof;

FIG. 10 is a top plan view thereof; and,

FIG. 11 is a bottom plan view thereof.
